Design No. 227,498

Patented June 26, 1973

James Edson McCanse and Stephen John Gecan

Application having been made by James Edson McCanse and Stephen John Gecan, the inventors named in the patent above identified and Hesston Corporation, Hesston, Kans., the assignee, for the issuance of a certificate under the provisions of Title 35, Section 256, of the United States Code, adding the name of Richard E. Ten Eyck as a joint inventor, and a showing and proof of facts satisfying the requirements of the said section having been submitted, it is this 10th day of January 1978, certified that the name of the said Richard E. Ten Eyck is hereby added to the said patent as a joint inventor with the said James Edson McCanse and Stephen John Gecan.
